CLAIM

The ornamental design for hand held vacuum pump for use in delivery rooms, as shown and described.

DESCRIPTION

FIG. 1 is a front perspective view of a hand held vacuum pump showing our new design, on an enlarged scale;

FIG. 2 is a left side elevational view thereof, the right side being a mirror image;

FIG. 3 is a front elevational view thereof;

FIG. 4 is a rear elevational view thereof;

FIG. 5 is a bottom plan view thereof; and

FIG. 6 is a top plan view thereof.

FIG. 1

FIG. 4
